CLAIM

The ornamental design for a Pilates exercise chair extender, as shown and described.

DESCRIPTION

FIG. 1 is a top front perspective view of the Pilates exercise chair extender, showing my new design.

FIG. 2 is a right bottom front perspective view thereof;

FIG. 3 is a top view thereof;

FIG. 4 is a bottom view thereof;

FIG. 5 is a front view thereof;

FIG. 6 is a back view thereof;

FIG. 7 is a left side view thereof; and,

FIG. 8 is a right side view thereof.

The dash-dot-dot broken lines shown in the figures are for the purpose of illustrating portions of the Pilates exercise chair extender which form no part of the claimed design.
